CASING FOR TAPE READER

Arlon G. Sangster, Sterling, Mass., assignor to
Jamesbury Corp., Worcester, Mass.

Filed Sept. 8, 1969, Ser. No. 19,048

Term of patent 14 years

Int. Cl. D14—02

U.S. Cl. D26—5

FIG. 1

FIG. 3

FIG. 2

FIG. 4

FIG. 5

FIG. 1 is a top plan view of a casing for tape reader showing my new design;

FIG. 2 is a front elevational view thereof;

FIG. 3 is an elevational view taken from one side thereof, the opposite side being a mirror image of the side shown;

FIG. 4 is a bottom plan view thereof; and

FIG. 5 is a front perspective view thereof.

I claim:

The ornamental design for a casing for tape reader, as shown.
